UNITED STATES PATENT OFFICE

PERCY L. DUNNAM, OF FORT WORTH, TEXAS

TOOL FOR REMOVING BROKEN VEHICLE AXLES

Application filed June 12, 1931. Serial No. 543,989.

The present invention comprehends the provision of a tool by means of which a broken automobile axle can be quickly and conveniently removed without entering or disturbing the differential mechanism in any manner whatsoever.

In accordance with the present invention, I provide a tool adapted to be inserted into one end of the axle housing, subsequent to the removal of one wheel and its associated axle section, the tool being constructed to obtain a powerful grip or purchase on the other axle section, so it can be removed from the housing with the tool, and with a minimum of both time and effort.

The nature and advantages of the invention will be better understood when the following detail description is read in connection with the accompanying drawings, the invention residing in the construction, combination and arrangement of parts as claimed.

In the drawings forming part of this application like numerals of reference indicate similar parts in the several views and where-
25 in:

Figure 1 is a view of the tool partly in section.

Figure 2 is an enlarged section taken on the line 2-2 of Figure 1.

30 Figure 3 is a similar section taken on the line 3-3 of Figure 1.

Figure 4 is a section taken on line 4-4 of Figure 1.

The tool forming the subject matter of the present invention embodies a hollow tubular member 10 of uniform diameter throughout its length, except at one end, where it is formed to provide a square opening, through which the clamping jaws slide. The opposite 35 end of the tubular member 10 has threadedly associated therewith, a cap 11 having a central opening to slidably receive the threaded section 12 of a shaft arranged within the member 10. The other section 13 of this shaft 40 is provided with a longitudinal threaded bore 14 opening at one end thereof, to accommodate the threaded section 12 as illustrated. The section 12 is provided with a head 15 through which is passed a rod 16 constituting 45 a handle.

Manifestly by rotating the section 12 in one or the other direction, the section 13 of the shaft is caused to move longitudinally of the tubular member, and in order to limit this movement of the shaft, the section 13 is 55 slotted as at 17, and receives the stop pin 18 terminally connected with the tubular member 10 as shown.

The outer end of the shaft section 13 is recessed as at 19 to receive the clamping jaws 20. The jaws are preferably formed from a single piece of suitable material, folded upon itself, and attached to the shaft by means of a pin 21 passed between the jaws at the closed end thereof, and through the 60 recess 19 of the shaft section 13. The corresponding free ends of the jaws are formed with inwardly directed gripping flanges 22.

In use of the tool for the purpose above mentioned, one wheel and its associated axle section is removed from the axle housing. The tool is then inserted in said housing through the open end thereof, with the jaws 20 open or spread apart. After the tool has been properly positioned within the axle housing, 70 that is, with the jaws 20 straddling the adjacent end of the axle section to be removed, the handle 16 is operated to rotate the threaded section 12 of the shaft, to move the jaws 20 inwardly of the tubular member 10. During this operation, the jaws are moved toward each other into gripping relation with the axle section to be removed, causing a powerful grip on the latter, so it can be easily removed from the axle housing together with 75 the tool. Obviously this duty can be readily and easily performed, without the necessity of either entering the differential housing, or otherwise interfering with the differential 80 mechanism. The tool is simple in construction, can be manufactured and sold at a nominal cost, and is very easy to handle and manipulate for the purpose intended.

While it is believed that from the foregoing description the nature and advantages of the invention will be readily apparent, I desire to have it understood that I do not limit myself to what is herein illustrated or described, and that such changes may be re- 95 100

sorted to when desired, as fall within the scope of what is claimed.

What I claim as new is:

1. A tool of the character described comprising a tubular member having a square opening at one end thereof, a shaft movable longitudinally within said member, a pair of normally open relatively movable jaws carried by one end of the shaft and slidable through the opening in the tubular member, means for operating said shaft to slide the jaws inwardly through said opening, whereby said jaws are moved into gripping relation, said shaft having a longitudinal slot, and a stop pin carried by said tubular member and passed through said slot, to limit the movement of said shaft in either direction.

2. A tool of the character described comprising a tubular member having a square opening at one end thereof, a shaft arranged in said member and including a slidable section and rotatable section, a pair of relatively movable jaws carried by one end of the slidable section and movable through the opening of said tubular member, said slid-
able section having a threaded bore opening at its inner end, said rotatable section being threaded in said bore, and means for rotating the latter mentioned section to slide said jaws inwardly through said opening of the tubular member, whereby said jaws are moved into gripping relation, and means for limiting the sliding movement of said section in either direction.

35 In testimony whereof I affix my signature.
PERCY L. DUNNAM.
